ANTIRATTLING ATTACHMENT FOR
WINDOWS

Awksent J. Sinchuk, Bridgeport, Conn.

Application June 27, 1939, Serial No. 281,357

1 Claim. (Cl. 292—76)

My invention relates to antirattling attachments for windows and has particular reference to devices for preventing rattling of windows by tightening them in the window frames.

My invention has for its object to provide a device which can be easily attached to a window sash and which will resiliently engage the window frame in such a manner that the window will be at all times pressed to one side of the frame. My attachment for this purpose consists of a spring member fastened to one side of the window sash and engaging the inside of a slot in the window frame, thereby pressing the sash against the other side of the frame in the slot.

My attachment has an added advantage in that the window sash, being at all times tightly pressed against the side of the slot in the frame, becomes largely wind-proof and thus prevents cold draft from passing into the room around the sash in the slot, helping also to conserve the heat in the room.

My invention is more fully described in the accompanying drawing and specification in which—

Fig. 1 is a sectional view of a portion of a window sash in the slot in a window frame, showing also my attachment.

Fig. 2 is a fractional front view of the same.

Fig. 3 is a detail end view of the attachment.

Fig. 4 is a fractional sectional view of a window sash and window frame with a modified antirattling attachment.

Fig. 5 is a fractional front view of the same.

Fig. 6 is an edge view of the attachment shown in Figs. 4 and 5.

Fig. 7 is an edge view of a modified attachment.

Fig. 8 is a front view of the same.

Fig. 9 is a sectional view of a window sash in a frame with a modified attachment.

Fig. 10 is a front view of the attachment shown in Fig. 9.

Fig. 11 is a front view of a modified attachment.

Fig. 12 is an edge view of the same.

Figs. 13 and 14 are views of a modified device.

Fig. 15 is a detailed view of another modification.

My attachment as shown in Figs. 1, 2 and 3 in one of its modifications, consists of a spring plate 1 preferably made of steel, galvanized, plated or otherwise rendered unoxidizable. Stainless carbon steel can be also used to advantage, as well as phosphor bronze or similar hard alloys. The plate has holes for screws 2 and 3 with which it is fastened to a window sash 4. The plate 1 is so shaped that it stands out from the side of the sash 4, being resiliently wedged between the sash

and the side of a slot 5 in a window frame 6. The free end of the plate 1 has a transversely enlarged portion 7 curved as shown so that it bears against the side of the slot 5 by its middle portion, the ends being bent away. This is important in order to prevent the ends of the sliding portion 7 from rubbing the side of the slot 5. The ends are bent out at 7' for the same purpose. The tension of the plate can be adjusted by the screw 2 which bears against the curved portion of the plate 1.

A modified device is shown in Figs. 4, 5 and 6. The spring plate 8 has an angular extension 9 of an arcuate shape so bent that it bears at its ends against the side of the window sash 4 while its middle raised portion bears against the inner side of the slot 5. The end 10 of the angular portion 9 is slightly raised in order to prevent the edges of the spring plate from scratching the inner side of the window frame 6.

Another modification is shown in Figs. 7 and 8, this being a wholly concealed type. The spring plate 11 is curved in the shape of an arc so that its ends rest against the side of the window sash 4 while the middle raised portion presses against the inner side of frame 6 in the slot 5. The ends of the plate 11 are slotted lengthwise at 12 for screws 13. The screws provide sufficient clearance under their heads to permit of a sliding movement of the plate 11 when it is depressed. This device must be mounted on the window sash 30 before the latter is fitted in its place in the window frame.

Another modification is shown in Figs. 9 and 10. A plate 14 has a roller 15 at the end of an angular extension 16, the roller engaging the inner side 35 of the slot 5. A groove 17 is provided for the roller 15 inside the slot 5. The roller can be also placed lengthwise of the plate 18 as shown in Figs. 11 and 12, the plate being fastened transversely of the window frame by screws fitted in 40 the holes 19.

Another modification is shown in Figs. 13 and 14. The device consists of a straight spring plate 20 with holes 19 for attaching it to the window sash, the roller 15 being used to provide sliding engagement with the inside surface of the frame in the slot 5. This form of the device has an advantage that it is fully concealed but it must be fitted in place with the window sash removed 50 from the frame.

Still another modification is shown in Fig. 15. The sash has a transverse bore for a metal tube 21. The roller 15 is fitted in a slide 22 in the tube 21 and is urged outward by a spring 23. This de- 55

vice also must be fitted into the sash when the latter is removed from the frame.

It is understood that my antirattling attachment for windows may be further modified without departing from the spirit of my invention as set forth in the appended claim.

I claim as my invention:

An antirattling attachment for a window comprising a T-shaped spring, the middle member of 10 the spring having holes at the end for screws for fastening the end of the member to a window

sash transversely to the edge of the sash, the middle member being bent so as to resiliently press against the inner side of a slot for the window sash in the window frame, the cross-member of the spring being curved longitudinally so as to place its end points away from the inner side of the slot, the pressure of the spring against the inner side of the slot being adapted to be adjusted by the screws.
